(57) **CLAIM**

The ornamental design for a combined plug and socket, as shown and described.

DESCRIPTION

FIG. 1 is a perspective view of a combined plug and socket, showing my new design;

FIG. 2 is a rear and top perspective view of a first piece of the combined plug and socket;

FIG. 3 is a front and bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a rear and top perspective view of a second piece of the combined plug and socket;

FIG. 11 is a front and bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is an exploded view thereof.

The broken lines in the figures illustrate portions of the combined plug and socket that form no part of the claimed design.
